United States Patent Office

Des. 213,271
Patented Jan. 28, 1969

213,271

SLIDE

John A. Gale, 978 Shady Lane, Wayzata, Minn. 55391

Filed Mar. 4, 1968, Ser. No. 10,843

Term of patent 14 years

U.S. Cl. D34—5

Int. Cl. D21—04

Des. 213,271

PAGE 2

FIG. 3

FIG. 4

FIG. 5

FIG. 1 is a perspective view of the slide incorporating my new design taken approximately from one corner of the base of the slide;

FIG. 2 is an elevation of the slide;

FIG. 3 is an elevation of the slide taken substantially from the right side of FIG. 2;

FIG. 4 is a top plan view of the slide; and

FIG. 5 is a bottom plan view of the slide.

I claim:

The ornamental design for a slide, substantially as shown.
